UNITED STATES PATENT OFFICE.

WATZE SPOELSTRA, OF SAN JOSE, CALIFORNIA.

AIR-HEATER.

1,361,351.

Specification of Letters Patent. Patented Dec. 7, 1920.

Application filed September 8, 1920. Serial No. 408,998.

To all whom it may concern:

Be it known that I, WATZE SPOELSTRA, a subject of the Queen of the Netherlands, and resident of San Jose, in the county of 5 Santa Clara and State of California, have invented certain new and useful Improvements in Air-Heaters, of which the following is a specification.

This invention relates to air heating apparatus; and it proposes, briefly, an improved heater which is especially designed for use in connection with drying apparatus for supplying heated air thereto.

According to the invention, a combustion 15 chamber or furnace is utilized in which the fuel is burned, this chamber being completely encircled by an annular air inlet passage which communicates with a main heating chamber into which the combustion 20 chamber opens. Both the annular air passage or chamber and the adjacent outer portion of the main heating chamber are fitted with tubes, the rear ends of the air chamber tubes and the front ends of the heating 25 chamber tubes being fitted in openings in a change header plate which conjointly forms the rear wall of the air chamber and the front wall of the main heating chamber. The air chamber is open at its front for 30 ingress of air, and the tubes therein project beyond said chamber and open into an annular chamber which encircles the front end of the combustion chamber and which communicates with a stack so as to produce the 35 required draft. The rear ends of the tubes in the main heating chamber open into an air collecting chamber from which the heated air passes through an exhauster and is piped to the drier or other point of use. 40 The air collecting chamber is preferably equipped with an auxiliary heating chamber which is located interiorly thereof and is provided with its own set of air inlet pipes; the air heated in the auxiliary chamber dis- 45 charging into the collecting chamber.

Owing to the above described construction and arrangement of parts, the air drawn in through the open-ended air chamber will circulate freely around the tubes therein 50 and which convey the flue gases or gases of combustion from the main heating chamber and discharge them into the annular chamber at the front of the combustion chamber, whence they pass to the stack. On reaching 55 the rear end of the air chamber, the air enters the tubes or flues disposed in the

main heating chamber and then flows into the collecting chamber; the disposition of the tubes or flues in the main heating chamber being such as to enable the flue gases 60 to circulate freely around and act directly on them, so that the air will be heated to the proper degree by the time it enters the collecting chamber, while the flue gases will have given up a part of their heat before 65 entering their exit tubes or flues. The currents of air and gas travel horizontally in opposite directions through their respective flues; the air passing through the air chamber entirely surrounding the gas flues or 70 tubes therein, while the flue gases in the main heating chamber entirely surround the air flues.

The auxiliary heating chamber has its front wall formed by the rear wall of the 75 main heating chamber, so that the air supplied to the former chamber through the auxiliary inlet tubes or flues will be rapidly heated. These auxiliary flues may be equipped with suitable regulating devices 80 to control the passage of the air therethrough and, hence, the amount of air received in the collecting chamber, thereby providing for semi-permanent regulation of the heater to the point of greatest efficiency. 85

Other improvements and advantages will become apparent in the course of the following description.

An embodiment of the invention is illustrated in the accompanying drawings, in 90 which:

Figure 1 is a central vertical section of the improved heater.

Fig. 2 is a front elevation thereof.

Figs. 3, 4, 5 and 6 are transverse vertical 95 sections taken, respectively, on lines 3-3, 4-4, 5-5 and 6-6, Fig. 1.

Fig. 7 is a rear end elevation.

Referring more particularly to said drawings, 1 designates the combustion chamber 100 of the apparatus, here shown as of cylindrical form and as provided with a lining 2 of fire brick or other refractory material. This chamber receives the fuel to be consumed, which is ignited and consumed in 105 the chamber, so that the flue gases or gases of combustion will be caused to pass rearward through the chamber into the subsequently-described main heating chamber 3. The combustion-chamber is provided with 110 suitable heating means 111 shown diagrammatically, in Fig. 1, as in the form of an

interiorly-located grate for supporting the fuel to be burned.

For the major portion of its length, the combustion chamber is encircled by an annular air chamber 4, which is open at its front end and the front edge of which is spaced a comparatively slight distance behind a second annular chamber 5, which encircles the extreme front portion of the combustion chamber and is closed by front and back plates 6 and 7, the outer or annular wall of this chamber 5 having a discharge opening 8 from which a flue 9 leads to the stack (not shown).

15 The rear end of the air chamber 4 is closed by a plate 10, hereinafter termed the change header plate, which conjointly forms the rear wall of that chamber, and the front wall of the previously-mentioned main heating chamber 3, which is likewise of cylindrical form and has a diameter equal to that of the outer wall of chamber 4,—in other words, the combined diameters of the combustion chamber and the air chamber 20 proper. The portion of the change header plate 10 which is immediately behind the combustion chamber 1, is left open.

25 The back plate 7 of the discharge chamber 5 is formed with a circular series of openings 11 which exactly aline with a coaxial series of openings 12 formed in the change header plate 10, these openings having fitted therein the corresponding ends of a series of horizontal tubes or flues 13 serving to convey the flue gases from the main heating chamber 3 through the air chamber 4 into the above-mentioned discharge chamber 5; the said flues being spaced substantially equidistantly of the walls of the air chamber, so that the in-coming air can circulate freely around and along them during its progress through the air chamber and be heated in that way. The header plate 10 has formed in it, in addition to the gas flue 30 inlets 12, a plurality of circular series or rows of openings 14, all of which additional rows are concentric with one another and with the intermediate row 12. These openings 14, the two inner rows of which have a 35 slightly smaller diameter than the remaining rows, receive the front ends of rows of tubes or flues 15, whose rear ends fit in corresponding openings 16 formed in the rear plate 17 of the main heating chamber 3; 40 both ends of the flues being left open, so that the air in the chamber 4 may be drawn therethrough and discharged into the collecting chamber 18 which is located immediately behind the chamber 3 and has the 45 same diameter as that chamber. The flues 15 are spaced sufficiently far apart from one another and from the wall of chamber 3 to permit them to be entirely surrounded by the flue gases in chamber 3 which are therefore 50 caused to give up a portion of their heat,

with the result that the air in passing through the flues is heated to the required temperature.

The central portion of the main heating chamber contains no flues, as will be understood from Figs. 1, 4 and 5; and the corresponding portion of the end header plate 17 which conjointly forms the rear wall of said chamber and the front wall of the collecting chamber 18 is removed, the opening thus produced being covered by a detachable plate 19. The latter forms the front wall of an auxiliary heating chamber 20, which is located within the chamber 18 and is supplied with air through an individual set of short inlet flues 21, which extend at their front ends through openings 22 in the rear plate 23 of chamber 20 and at their rear ends through openings 24 in the rear plate or end header plate 25 of the collecting chamber 18. The flue openings 22 are disposed comparatively close to the edge of plate 23, which latter is further provided with a central discharge opening 26 for the escape of the heated air into the collecting chamber, from which it passes through an opening 27 in the end header plate or rear plate 25 into an exhauster (not shown) which supplies it to its point of use.

The plates which form the front and rear walls of the several chambers may be made in sections for convenience of construction, and for replacement of tubes, as will be understood from Figs. 2 to 5 and 7; the air passage or chamber 4 may be subdivided 100 into a number of separate passages, if desired; and various other minor changes or additions may be resorted to within the scope of the invention.

Means are provided in connection with 105 the auxiliary inlet flues or tubes 21 for controlling the air flow therethrough, said means being here shown as in the form of caps 28 (indicated in dotted lines in Fig. 1) which may be removably attached to any or 110 all of these tubes. The tubes left opened or uncapped bring in air of lower temperature for admixture in the collecting chamber with the air supplied thereto through the main flues 15, so that the temperature of the 115 air withdrawn through the opening 27 is the resultant of such admixture. Hence by varying the number of auxiliary tubes left open, the temperature at which the air is piped off from the header may be correspondingly modified within certain limits, 120 thereby providing for a regulation to the point of greatest efficiency.

I claim as my invention:—

1. An air heater, comprising in combination, a combustion chamber; an annular air inlet passage encircling the same; a heating chamber located immediately behind the combustion chamber and in free communication therewith to permit the 130

gases of combustion to pass from the combustion chamber to the heating chamber; a series of flues arranged in the air passage and opening at their inlet ends into the heating chamber to convey the heated gases from said heating chamber through said passage and thereby heat the incoming air flowing through the passage; a series of air flues arranged in said heating chamber and around which the heated gases in the heating chamber freely circulate prior to their entry into the gas flues, said air flues opening at their inlet ends into said air passage; and an air collecting chamber behind said heating chamber and into which the outlet ends of the air flues open.

2. An air heater, comprising in combination, a combustion chamber; an annular air inlet passage encircling the same; a heating chamber located immediately behind the combustion chamber and in free communication therewith to permit the gases of combustion to pass from the combustion chamber to the heating chamber, a series of flues arranged in the air passage and opening at their inlet ends into the heating chamber to convey the heated gases from said heating chamber through said passage and thereby heat the incoming air flowing through the passage; a gas discharge chamber encircling the front of the combustion chamber and into which the outlet ends of the gas flues open, said discharge chamber adapted for connection to a stack to create a draft therein; a series of air flues arranged in said heating chamber and around which the heated gases in the heating chamber freely circulate prior to their entry into the gas flues, said air flues opening at their inlet ends into said air passage; and an air collecting chamber behind said heating chamber and into which the outlet ends of the air flues open.

3. An air heater, comprising in combination, a combustion chamber; an annular air inlet passage encircling the same; a heating chamber located immediately behind the combustion chamber and in free communication therewith to permit the gases of combustion to pass from the combustion chamber to the heating chamber; a series of flues arranged in the air passage and opening at their inlet ends into the heating chamber to convey the heated gases from said heat-

ing chamber through said passage and thereby heat the incoming air flowing through the passage; a series of air flues arranged in said heating chamber and around which the heated gases in the heating chamber freely circulate prior to their entry into the gas flues, said air flues opening at their inlet ends into said air passage; an air collecting chamber behind the heating chamber and into which the outlet ends of the air flues open; an auxiliary heating chamber located in said air collecting chamber immediately behind the first-named heating chamber to be heated thereby; and means independent of said air flues for supplying air to the auxiliary chamber to be heated therein.

4. An air heater, comprising in combination, a combustion chamber; an annular air inlet passage encircling the same; a main heating chamber in communication with the combustion chamber to receive the heated gases of combustion therefrom; means for conveying said gases from said heating chamber through said air passage to heat the air flowing therethrough; an air collecting chamber; means for conveying the air from said passage through said heating chamber and into said collecting chamber; and an auxiliary heating chamber located within said collecting chamber and having an air supply means individual thereto.

5. An air heater, comprising, in combination, a combustion chamber; an annular air inlet passage encircling the same; a main heating chamber in communication with the combustion chamber to receive the heated gases of combustion therefrom; means for conveying said gases from said heating chamber through said air passage to heat the air flowing therethrough; an air collecting chamber; means for conveying the air from said passage through said heating chamber and into said collecting chamber; an auxiliary heating chamber located within said collecting chamber; a series of air inlet flues individual to the auxiliary heating chamber for supplying air thereto; and means associated with the individual air inlet flues for controlling the flow of air therethrough.

In testimony whereof I affix my signature.

WATZE SPOELSTRA.
